ELECTRIC SWITCH

Filed July 21, 1945

Fig. 1. 4

UNITED STATES PATENT OFFICE

2,455,927

ELECTRIC SWITCH

Stephen S. Grady, New York, N. Y.

Application July 21, 1945, Serial No. 606,369

6 Claims. (Cl. 200—67)

1

This invention relates to electric switches in general and more especially to toggle switches.

Among the objects of the present invention, it is aimed to provide an improved electric switch of the toggle or snap switch type in which the main contacts may be disengaged without interrupting the current and thereby in turn practically eliminate the arc formation, and confine the arc formation, if any, to a quick breaking narrow area.

It is still another object of the present invention to provide an improved electric switch of the toggle or snap switch type having main and auxiliary contacts, the auxiliary contacts being engaged first in circuit making action and disengaged last in circuit interrupting action to eliminate arc formation between the main contacts either during the making or breaking of the circuit.

It is still another object of the present invention to provide an improved electric switch having main contacts which engage face to face, one of which main contacts is yieldable to cause the contacting faces to move relative to one another while in engagement with one another during making and breaking of a circuit in turn to clean the surfaces of any accumulation of dirt or foreign material.

These and other features, capabilities and advantages of the invention will appear from the subjoined detail description of one specific embodiment thereof illustrated in the accompanying drawings in which

Fig. 1 is a front elevation of the switch in closed position;

Fig. 2 is a rear elevation of the switch in closed position;

Fig. 3 is a section on the line 3—3 of Fig. 1;

Fig. 4 is a section on the line 4—4 of Fig. 1;

Fig. 5 is a rear elevation of the switch with the handle partly moved into a position before breaking the contact.

In the embodiment shown, there is provided a casing having a base 1 to which are connected two side walls 2 and 3. On the base there are mounted two brackets 4 and 5 connected to the terminals (not shown) of the switch. The contact bracket 4 has the flange 6 with an opening therein to receive a screw or the like to connect the flange 6 to the base 1 and the bearing bracket 5 in the present instance has a flange 7 provided with a recess 8 to receive a screw or the like to connect the flange 7 to the base 1. The brackets 4 and 5 are in turn insulated from one another by, and connected to the insulation block

2

9. The bracket 4 has a connecting portion 10, double thickness in the present instance, connected to the block 9 by screws such as the screw 11, and the bracket 5 in turn has a flange 12 connected to the block 9 by screws such as the screw 13. The bracket 4 in the present instance constitutes the first contact of the switch and is provided with two contacting sections, to wit, the narrow section 14 and the wide section 15 or plate 15 connected to one another by the connecting portion 10. The wide section 15, in the present instance, is separated from the connecting portion 10 by the slot 16, which extends down to the point 17, see Fig. 1, in order that the section 15 is free to yield when engaged by the flange 18 constituting one of the movable contacts of the switch. When so yielding upon initial contact, a wiping or rubbing action will take place between the engaging faces of the plates 15 and 18 to free the engaging surfaces from any carbon that might collect as a result of arcing during making or breaking of the circuit.

The movable contact 18 in the present instance is formed on the blade 19 pivotally connected by the pin 20 to the flange 21 on the bracket 5. The blade 19 has an opening 22 therein, the ends of which cooperate with the pin or projection 23 on the arm 24 pivotally connected at 25 to the flange 26 formed on the bracket 5. The bar 24 extends downwardly from the flange 26 and the lower edge thereof in the contact making position shown in Figs. 1 and 2 engages the narrow fixed contact area 14 of the bracket 4. The blade 19 and the arm 24 cooperate with the pivot pins 20 and 25 and the spring 27 to constitute a toggle leverage which will be locked in place to either side of the pivot pin 25 by the spring 27 in the usual way, the one end of the spring being connected to the projection 28 in the present instance alining with the pin 23, and the other end of the spring being connected to the projection 29 formed on the blade 19 on the other side of the pivot point 25.

Preferably for manipulating the blade 19, it is provided with a handle 30 composed of insulating material which has the arcuate shield extensions 31 and 32 preferably integral with the handle 30 and also composed of insulating material. The shield portions 31 and 32 thus serve in a way to protect the fingers of the user from any short circuit or arc that might be created during the making or breaking of the circuit in the act of opening or closing the circuit.

The pin 25 extends through the upper portion 55 of the insulating block 9 from the flange 26 to

the contact disk 33 which is in wiping contact with the blade 19.

The block 9 is provided with a slot 34 to form a clearance for the pin 23, and, see Fig. 4, is also provided with a slot 35 to form a clearance for the lower end of the arm 24 by effectively insulating the lower end of the arm 24 from the bracket 4 when the switch is in open position. Preferably as shown, the insulating block may be composed of two parts, the part 36 and the angle strip 37 having the web 38 secured to the bottom of the part 36 and the web 39 spaced from the bottom of the part 36 to form a clearance between the web 39 and the part 36 for the lower end of the arm 24.

The lower portion 40 of the insulation part 36, as is clearly shown in Fig. 4, separates the arm 24 from the blade 19 so that, see Fig. 3, after the switch has been closed, both the flange 18 engages the plate 15, and the blade 24 engages the portion 14 of the bracket 5. Then upon starting to open the switch, see Fig. 5, the blade 19 will first cause the flange 18 to clear the plate 15 when the current will continue to flow from one terminal to the other through the arm 24 and contact portion 14 of the bracket 5 and the switch will not be opened until the blade 19 has moved the abutment 29 of the spring 27 so that the spring 27 will pass to the other side of the dead center or pivot pin 25 to cause the arm 24 quickly to snap out of contact with the portion 14 and move over into the open position where the pin 23 approaches the other end of the recess 22, namely the end 41, when the lower end of the arm 24 will engage the inner face of the bracket 4.

When again actuating the blade 19 to close the switch, the end 41 of the recess 22 will first move into engagement with the pin 23 and after engaging the same cooperate with the spring 27 to swing the lower end of the arm 24 into engagement with the contact portion 14 of the bracket 4, the spring 27 of course entering into play as soon as it passes the dead center or pivot pin 25 in the well known action of a toggle. In the final position of the blade 19, see Fig. 2, the spring 27 will also operate or function to cause the flange 18 to engage the plate 15.

In operation it will thus be seen that when the switch is closed, the current will pass from a terminal of the conductor, not shown, connected to the bracket 4 either through the plate 18 to the flange 15 of the blade 19, then from the blade 19 through the bracket 5 to the other terminal or else when the blade 19 has caused the flange 18 to be spaced from the plate 15 then the current will pass from the bracket 4 through the contact portion 14 to the arm 24 and then from the arm 24 pivotally connected to the bracket 5 through the bracket 5 to the other terminal of the conductor. In this way, when the blade 19 is in its closed position as shown in Fig. 2, the extended area of the flange 15 will cooperate with the blade 18.

From the foregoing it will thus appear that the initial make and break of the circuit will be effected by the edge of the arm 24 engaging the portion 14 of the bracket 4, a comparatively narrow surface, and the make and break with the edge of the arm 24 will be an exceedingly fast one so that if an overload did occur, before it could cause any harm to the switch, in the opening of the switch, the spring 27 would come into play to cause the switch to open immediately, and in turn, when closing the switch, also

while the arm 24 may be the first to establish a current through the area 14 of the bracket 4, the successive contact between the flange 18 and plate 15 will follow so quickly after initial contact is made that no harm can come to the switch, and on the other hand, when the extended face of the flange 18 engages the plate 15, then a sufficiently large area will be in contact to reduce the resistance and effectively take care of an ordinary overload without injury to the switch. In turn, upon opening of the switch, due to the fact that the arm 24 will still be in contact with the portion 14 of the bracket 4 when an extended surface of the flange 18 recedes from the plate 15, see Fig. 5, no arc will take place during this opening movement. Furthermore, if any dirt or foreign material should have collected on the faces of the flange 18 and plate 15, such dirt or foreign material will be wiped off or rubbed off, due to the yieldability of the plate 15 and relative movement of the plate 15 and flange 18 as a result of this flexibility while the flange 18 is making contact with the plate 15 or leaving the plate 15. In other words, when the flange 18 initially engages the plate 15, before the two come to rest, there will be a surface movement of one relative to the other due to the yieldability of the plate 15 which surface movement will again occur when the blade 19 is started on its movement to open position.

It is obvious that various changes and modifications may be made to the details of construction without departing from the general spirit of the invention as set forth in the appended claims.

I claim:

1. The combination of a bearing bracket constituting one terminal of an electric circuit, a blade and an arm pivotally connected at spaced 40 apart portions of said bearing bracket, a spring connected at one end to said arm and at its other end to said blade, a contact bracket constituting the other terminal of an electric circuit, the spring being positioned to one side 45 of the pivotal connection of said arm when said blade and arm are spaced from said contact bracket, said contact bracket having a flexible contact plate, and a contact flange on said blade, the spring being positioned to one side of the 50 pivotal connection of said arm when said arm and blade are maintained in open switch position and said spring being positioned to the other side of the pivotal connection of said arm when said spring yieldably maintains the free end of 55 said arm in contact with said contact bracket and the flange of said blade in contact with said flexible plate, said blade being movable relative to said arm so that said flange may be withdrawn out of contact with said flexible plate before the 60 free end of said arm is withdrawn from contact with said contact bracket.

2. The combination of a bearing bracket constituting one terminal of an electric circuit, a blade and an arm pivotally connected to said bracket, 65 a spring connected at one end to said arm and at its other end to said blade, a contact bracket constituting the other terminal of an electric circuit, the spring being positioned to one side of the pivotal connection of said arm when said blade and arm are spaced from said contact bracket, said contact bracket having a flexible contact plate, a contact flange on said blade, the 70 spring being positioned to one side of the pivotal connection of said arm when said arm and blade 75 are maintained in open switch position and said

spring being positioned to the other side of the pivotal connection of said arm when said spring yieldably maintains the free end of said arm in contact with said contact bracket and the flange of said blade in contact with said flexible plate, said blade having an opening therein with abutments at the ends thereof, and a projection on said arm extending into said opening and cooperating with said abutments and said spring to snap said arm and blade into open or closed position immediately that said spring passes the pivotal connection of said arm.

3. The combination of a bearing bracket constituting one terminal of an electric circuit, a blade and an arm pivotally connected at spaced apart portions of said bearing bracket, a spring connected at one end to said arm and at its other end to said blade, a contact bracket constituting the other terminal of an electric circuit, the spring being positioned to one side of the pivotal connection of said arm when said blade and arm are spaced from said contact bracket, said contact bracket having a flexible contact plate, a contact flange on said blade, the spring being positioned to one side of the pivotal connection of said arm when said arm and blade are maintained in open switch position and said spring being positioned to the other side of the pivotal connection of said arm when said spring yieldably maintains the free end of said arm in contact with said contact bracket and the flange of said blade in contact with said flexible plate, and an insulated extension on said blade to serve as a handle for actuating the blade.

4. The combination of a bearing bracket having two flanges at its opposite ends and constituting one terminal of an electric circuit, a blade pivotally connected to one of said flanges and extending to and beyond the other flange, an arm pivotally connected to said other flange and extending parallel to said one flange, a spring connected at one end to said arm below its pivotal connection with said other flange and connected to said blade beyond said other flange, a contact bracket constituting the other terminal of the electric circuit, a flexible plate formed on said contact bracket, and a flange formed on said pivotal blade and contacting said flexible plate when the spring is positioned to one side of the pivotal connection to close the circuit when the free end of said arm also contacts said contact bracket.

5. The combination of a bearing bracket having flanges at its opposite ends and constituting one terminal of an electric circuit, a blade pivotally connected to one of said flanges and extending to and beyond the other flange, an arm pivotally connected to said other flange and extending parallel to said one flange, a spring con-

nected at one end to said arm below its pivotal connection with said other flange and connected to said blade beyond said other flange, a contact bracket constituting the other terminal of the electric circuit, a flexible plate formed on said contact bracket, a flange formed on said pivotal blade and contacting said flexible plate when the spring is positioned to one side of the pivotal connection to close the circuit when the free end of said arm also contacts said contact bracket, there being an opening in said pivotal blade having abutments at its opposite ends, and a projection on said arm cooperating with said abutments and said spring to snap said arm and pivotal blade into and out of closed position.

6. The combination of a bearing bracket having flanges at its opposite ends and constituting one terminal of an electric circuit, a blade pivotally connected to one of said flanges and extending to and beyond the other flange, an arm pivotally connected to said other flange and extending parallel to said one flange, a spring connected at one end to said arm below its pivotal connection with said other flange and connected to said blade beyond said other flange, a contact bracket constituting the other terminal of the electric circuit, a flexible plate formed on said contact bracket, a flange formed on said pivotal blade and contacting said flexible plate when the spring is positioned to one side of the pivotal connection to close the circuit when the free end of said arm also contacts said contact bracket, there being an opening in said pivotal blade having abutments at its opposite ends, and a projection on said arm cooperating with said abutments and said spring to snap said arm and pivotal blade into and out of closed position, said pivotal blade being movable relative to said arm to withdraw said flange from said flexible plate before said arm is withdrawn from said contact bracket in circuit interrupting operation, and said flexible plate and flange being movable relative to one another when in contact with one another to remove any deposits of dirt or foreign material.
